UNITED STATES PATENT OFFICE.

WILLIAM HOOPES, OF PITTSBURGH, PENNSYLVANIA.

CONDENSER-TUBE-CLEANING APPARATUS.

1,172,798.

Specification of Letters Patent. Patented Feb. 22, 1916.

Application filed April 6, 1915. Serial No. 19,483.

To all whom it may concern:

Be it known that I, WILLIAM HOOPES, a citizen of the United States, residing at Pittsburgh, in the county of Allegheny and 5 State of Pennsylvania, have invented an Improvement in Condenser-Tube-Cleaning Apparatus, of which the following is a specification.

My present invention relates to apparatus 10 for cleaning condenser tubes, and particularly the tubes of surface condensers, through which, as is well known in the art, water or other fluid is made to circulate in order to condense the steam, which is caused 15 to enter the body of the condenser and come into contact with the outer surface of the tubes.

Various devices, including rods, brushes, and similar articles, have heretofore been 20 employed for cleaning the tubes of surface condensers, but so far as I am aware, in the use of all such devices it has been necessary to open one or both ends of a condenser in order to gain access to the tubes. 25 Now, the object of my present invention is the provision of an apparatus built as an integral part of the condenser, and which may be utilized, when necessary, for cleaning the condenser tubes.

In carrying out my invention, I preferably employ, in combination with the water box, ordinarily employed with surface condensers, a movable member, which is adjustable to position within the water box, 30 and through and by which a suitable fluid, for example, water, steam or compressed air, under pressure, may be injected into and forced through the condenser tubes to clean the same.

Furthermore, my invention also includes 35 means for suitably actuating this adjustable member from the exterior of the apparatus, all of which will be hereinafter more particularly described.

In the drawing, Figure 1 is a vertical 40 cross section taken approximately through the center of a condenser water box fitted with my improved tube cleaning apparatus.

Fig. 2 is a transverse cross section, and Fig. 45 3 is a partial cross section and elevation taken at right angles to the position of the parts as shown in Fig. 1.

In the drawing, 10 indicates the condenser body or shell, only a portion of which is illustrated, but as will be understood,

this is the usual surface condenser body. At its opposite open ends, the condenser body 10 is provided with tube plates, one of which is indicated at 11, and between which, and as is customary, suitable tubes 12 extend, being secured in any desired manner at their respective ends in the tube plates.

At one end of the condenser, the same is provided with a bonnet having a partition plate for directing the flow of the circulating water, and at the other end with a water box, through which the circulating water passes from one bank of tubes to the other. In the drawing, this water box is indicated at 13, and is provided with a cover 14 to close the otherwise open end thereof. The parts to which reference has hereinbefore been made are all old in the surface condenser art. Within the water box 13 I employ an adjustable hollow head, indicated at 15. The ends 16 of this hollow head are grooved longitudinally, as shown at 17, in order to receive guide bars 18 fixed in the inner side walls of the water box by means of screws or bolts 19, in order that by the apparatus hereinafter described, the hollow head 15 may be moved vertically to any desired position within the water box. The respective ends of the hollow head 15 are also provided with tapped bores 20 passing longitudinally therethrough, and adapted to receive screw rods 21. The upper end of each screw rod 21 is swiveled in the bearing cap 22, fixed on the top of the water box. The lower ends of the rods 21 pass through and turn in tapped caps 23, fixed in the bottom of the water box, and exteriorly thereof each rod 21, at its lower end, is fitted with a worm wheel 24. I also employ a shaft 25, mounted in bearings 26, carried by hangers or brackets 27 secured to and depending from the bottom of the water box. In suitable positions, the shaft 25 is fitted with worms or endless screws 28, meshing respectively with the worm wheels 24. The shaft 25, by a coupling 29, may be connected to a motor 30, or other actuating apparatus, by which, when causing the shaft to turn in the required direction, the screw threaded rods 21 may be turned to either raise or lower the hollow head 15.

As is customary in surface condensers, the tubes are preferably fixed in the tube

plates in a staggered relationship, and in order to direct a fluid under pressure from the hollow head 15 to and through any of the tubes, I prefer to employ a plurality 5 of nozzles 31, also fixed in a staggered relationship on that side of the hollow head adjacent the ends of the tubes, in order that when the hollow head is properly placed, each nozzle 31 will be in alinement 10 with a condenser tube.

In order to convey a suitable fluid under pressure to the hollow head 15, I employ a pipe 32, which, at one end, extends through an opening provided therefor in the bottom 15 of the hollow head and is secured in place relatively thereto by having a flange 33, which is received in a recess provided therefor in a boss on the under side of the hollow head, together with a collar plate 34, 20 which fits over the pipe 32 and may be secured in position on the said boss by bolts 35, or otherwise. The pipe 32 extends through a suitable stuffing box 36, in the bottom of the water box, and exteriorly thereof 25 is provided with a handle 37, or other means, by which the pipe may be turned.

Within the hollow head 15 the pipe 32 is provided with a port 38, which, as shown in the drawing, is substantially semi-circumferential in extent, in order, as will be appreciated, to enable the operator to direct the fluid under pressure to either one side or the other of the hollow head or simultaneously to both sides thereof. At its outer 35 end, the pipe 32 may be fitted with a suitable screw-thread 39, for attachment to a coupling or other means by which the same may be connected to a suitable source of water or other fluid under pressure.

40 It is to be understood that while I have illustrated a hollow head adjustable vertically within the water box of the condenser, that the same may be adjustable horizontally, and that in either event any suitable 45 mechanism may be employed exteriorly of the condenser for adjusting the hollow head to position in the water box without departing from the nature or spirit of my invention, and also that my invention is applicable 50 to surface condensers which are circular in cross section, as well as to those which are rectangular in cross section, as herein shown and described.

55 I claim as my invention:

1. In a surface condenser and in combination, a water box, an injector head adjustable to position within the water box and having a plurality of openings therein adapted to register with the tubes of the 60 condenser, and a pipe fixed at one end in the said injector head and adapted to turn therein, the said pipe passing through the body of the water box so as to supply a fluid under pressure thereto from the exterior of the condenser.

2. In a surface condenser and in combination, a water box, an injector head adjustable to position within the water box, a plurality of nozzles fixed in and extending from one side of said injector head and adapted 70 to register with predetermined tubes of the condenser, guides within the water box and in which the injector head is movable in being adjusted to position, and a pipe fixed at one end in said injector head and adapted 75 to turn therein, the said pipe passing through the body of the water box so as to supply the fluid under pressure thereto from the exterior of the condenser.

3. In a surface condenser and in combination, a water box, an injector head therein, guides within the water box and on which the said injector head is movable, means operated exteriorly of the water box for determining the position of the injector head 85 therein, a plurality of nozzles fixed in and projecting from one side of the injector head and adapted to register with predetermined tubes of the condenser, and a pipe fixed at one end in said injector head and adapted 90 to turn therein, the said pipe having a port in that portion thereof that lies within the injector head and which, exterior of the injector head, passes through the body of the water box so as to supply a fluid under 95 pressure thereto from the exterior of the condenser.

4. In a surface condenser and in combination, a water box, an injector head adjustable to position within the water box, guides 100 in which the said injector head is movable within the water box, a plurality of nozzles fixed in one side of the said injector head in a staggered relationship corresponding to the positions of the adjacent rows of 105 condenser tubes, screw-threaded rods passing through the opposite ends of the said injector head and adapted to turn in the body of the water box, means exteriorly of 110 the water box for turning the said rods to 115 raise and lower the said injector head, and means for supplying a fluid under pressure to the said injector head.

5. In a surface condenser and in combination, a water box, an injector head adjustable to position within the water box, guides in which the said injector head is movable within the water box, a plurality of nozzles fixed in one side of the said injector head in a staggered relationship corresponding 120 to the positions of the adjacent rows of condenser tubes, screw-threaded rods passing through the opposite ends of the said injector head and adapted to turn in the body 125 of the water box, means exteriorly of the water box for turning the said rods to raise and lower the said injector head, a worm wheel attached to each of the said rods exteriorly of the water box, a shaft, worms thereon meshing with the said worm wheels, 130

means for turning the said shaft, and means for supplying a liquid under pressure to the interior of the said injector head.

6. In a surface condenser, and in combination, a water box, an injector head adjustable to position within the water box, means operated exteriorly of the water box for determining the position of the said injector head, and a pipe fixed at one end in the said injector head and adapted to turn therein and pass through the body of the said water box so as to supply a fluid under pressure thereto from the exterior of the condenser.

7. In a surface condenser and in combination, a water box, an injector head adjustable to position within the water box, means

operated exteriorly of the water box for determining the position of the said injector head, and a pipe extending into the said injector head and provided therein with a port so that upon being turned in the said injector head, a fluid under pressure supplied to the said pipe, exteriorly of the condenser, may be directed to either side of the injector head and also to both sides thereof simultaneously.

Signed by me this 24th day of March, 1915.

WILLIAM HOOPES.
